(57) **CLAIM**

The ornamental design for a bib as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of a bib in accordance with an embodiment of my new design;

FIG. 2 is a rear elevational view of the bib illustrated in FIG. 1;

FIG. 3 is a left side elevational view of the bib illustrated in FIG. 1;

FIG. 4 is a right side elevational view of the bib illustrated in FIG. 1;

FIG. 5 is a top plan view of the bib illustrated in FIG. 1;

FIG. 6 is a bottom plan view of the bib illustrated in FIG. 1;

FIG. 7 is a perspective view of the bib illustrated in FIG. 1;

FIG. 8 is another perspective view of the bib illustrated in FIG. 1, as viewed from a different angle from the perspective view of FIG. 7;

FIG. 9 is a cross-sectional view of the bib illustrated in FIG. 1, taken along 9-9 line shown in FIG. 1;

FIG. 10 is a cross-sectional view of the bib illustrated in FIG. 1, taken along 10-10 line shown in FIG. 1;

FIG. 11 is an enlarged front elevational view of a portion of the bib illustrated in FIG. 1;

FIG. 12 is an enlarged left side elevational view of a portion of the bib illustrated in FIG. 3;

FIG. 13 is an enlarged cross-sectional view of a portion of the bib illustrated in FIG. 9;

FIG. 14 is an enlarged cross-sectional view of a portion of the bib illustrated in FIG. 9;

FIG. 15 is an enlarged perspective view of a portion of the bib illustrated in FIG. 8;

FIG. 16 is a front elevational view of a bib in accordance with another embodiment of my new design that is made of a translucent material;

(Continued)

FIG. 17 is a rear elevational view of the bib illustrated in FIG. 16;

FIG. 18 is a left side elevational view of the bib illustrated in FIG. 16;

FIG. 19 is a right side elevational view of the bib illustrated in FIG. 16;

FIG. 20 is a top plan view of the bib illustrated in FIG. 16;

FIG. 21 is a bottom plan view of the bib illustrated in FIG. 16;

FIG. 22 is a perspective view of the bib illustrated in FIG. 16;

FIG. 23 is a front elevational view of a bib in accordance with yet another embodiment of my new design that is shown in a brown color;

FIG. 24 is a rear elevational view of the bib illustrated in FIG. 23;

FIG. 25 is a left side elevational view of the bib illustrated in FIG. 23;

FIG. 26 is a right side elevational view of the bib illustrated in FIG. 23;

FIG. 27 is a top plan view of the bib illustrated in FIG. 23;

FIG. 28 is a bottom plan view of the bib illustrated in FIG. 23; and,

FIG. 29 is a perspective view of the bib illustrated in FIG. 23.

The embodiment shown in FIGS. 16 to 22 is identical to the embodiment shown in FIGS. 1 to 15, except that the embodiment is made of a translucent material.

The embodiment shown in FIGS. 23 to 29 is identical to the embodiment shown in FIGS. 1 to 15, except that the embodiment is shown in a brown color.
